ORLANDO JENNINGS, OF NORTH SAN JUAN, CALIFORNIA.

Letters Patent No. 91,638, dated June 22, 1869.

IMPROVED MINING-SLUICE FOR SAVING SULPHURETS.

The Schedule referred to in these Letters Patent and making part of the same.

To all whom it may concern:

Be it known that I, ORLANDO JENNINGS, of North San Juan, county of Nevada, State of California, have invented an Improved Mining-Sluice; and I do hereby declare the following description and accompanying drawings are sufficient to enable any person skilled in the art or science to which it most nearly appertains, to make and use my said invention or improvement without further invention or experiment.

My invention relates to certain improvements in mining-sluices, for concentrating the heavier portion of ores, as sulphurets, fine gold, quicksilver, and amalgam, and separating them from the lighter and worthless portion; and

It consists in constructing the sluice in sections, and cutting channels in their bottoms, in such a manner, that as the heavier particles settle to the bottom, they are caught in these grooves and directed to some point of discharge, while that portion which is carried over the channels and still contains a portion of the metals, falls upon a second sluice of similar construction, placed at the end of the first, while the sand and worthless portion pass off at one side.

To more fully illustrate and explain my invention, reference is had to the accompanying drawings, forming a part of this specification, of which—

Figure 1 is a top view.

Figure 2 is a vertical longitudinal section.

Figure 3 is an end view.

Similar letters of reference in each of the figures indicate like parts.

A and B are two sections of a sluice.

These sections are joined together at their ends, so that each succeeding one shall be lower than the one directly in front of it, the lower one, B, being placed a little to one side, so as to leave a space for the lighter stuff to pass off to the outside of the sluice.

The bottoms of these sections are provided with any number of channels, $b' b' b''$, cut diagonally across the sluice. The lower side of these channels is raised so as to form riffles $e' e' e$, running parallel to them.

The section B is secured to the section A, so that the side d will be between the two sides of A, leaving a space, a , through which the lighter portion of the ore passes off at the end of each section.

A channel, g , commencing at the lower end of the first diagonal channel b , extends longitudinally with the section next to the side of the sluice into which each of the diagonal channels empty, and increases in area of cross-section in the ratio of the area of cross-section of each groove or riffle that feeds it, to the end where it empties into an opening, i , between the two sections.

The number of these sections may be increased to any extent, so as to insure the thorough extraction of the heavy particles.

The operation may be described as follows:

As a preliminary preparation of the ore before concentration, a proper sizing is indispensable, which can be done in pointed boxes, or by any well-known method, after which, for each size, a separate set of sluices is required, with the proper grade and amount of water that experience shows to be necessary.

The ore is then put on thinly at the head of the sluice, and evenly distributed over three-quarters or more of the entire width on the opposite side, to the longitudinal channel g , and clear water is introduced at the opposite side, or over the channel g .

The water, sand, and sulphurets, start down the sluice, and fill the grooves and above the riffles, a portion being deflected to the lower side along the channels. It thus continues to move until the sulphurets find their way by their specific gravity to the lowest part of the channels $b' b' b''$.

The sand is carried along over the channels and riffles, while the sulphurets move down into the channel g , and down it until it falls through the opening i , into another sluice or box beneath.

That portion of sand that may be considered exhausted of its sulphurets, passes out of the sluice to waste at a , which opening may be varied by a gate or other suitable device, so as to discharge more or less, as desired.

The portion of ore which falls upon the second section will be separated in the same manner as that on the first.

Having thus described my invention,

What I claim, and desire to secure by Letters Patent, is—

1. A sluice having the channels $b' b' b''$, and parallel riffles $e' e' e$, either diagonal in one direction, or diverging from or converging to the centre, and leading into the longitudinal channel or channels g , on one or both sides, or in the centre of the sluice, substantially as and for the purpose described.

2. Connecting the section of a sluice, B, so that the side d will be between the two sides of the sluice A, substantially as and for the purpose described.

In witness whereof, I have hereunto set my hand and seal.

ORLANDO JENNINGS. [L. S.]
